UNITED STATES PATENT OFFICE

ARVID WICKSTROM, OF DULUTH, MINNESOTA

WINDSHIELD WIPER

Application filed September 17, 1927. Serial No. 220,176.

This invention relates to window cleaners and has special reference to one particularly adapted for use on the windshield of an automobile.

5 Among various advantages of the novel construction which will appear in the further description is that of a form of heating element which will afford rapid and most efficient heating.

10 Referring now to the accompanying drawings, forming part of this application, and wherein like reference characters indicate like parts:

Figure 1 is a perspective view of a fragmental portion of the windshield wiper, or squeegee;

15 Figure 2 is a side elevation of the heating element showing the form of attachment of wire thereto;

20 Figure 3 is an enlarged transverse sectional view of a modified form of squeegee; and

Figure 4 is a fragmental portion of the body of the modified form showing how the rubber holder is formed.

25 1 represents the body portion of the squeegee which is preferably substantially cylindrical in form but open at one edge, the sides of the body portion adjacent the edge being extended and spaced from each other. Within

30 this metal body portion is a similarly shaped lining 2 of suitable insulating material, and these are formed in such a manner that a longitudinal slot is provided intermediate of the extended spaced terminals of the combined body and lining. Into this slot is placed

35 the heating element 3 which forms the scraper and the glass engaging edge may be sharpened or beveled in any desired manner for removing obstructions upon the glass; this device being particularly adapted for the removal of ice, frost or the like.

The novel feature of the heating element 3 which is also the cleaning member is that it comprises a thin flat piece of readily heated metal, that portion thereof extending beyond the impinging edges of the holder or body portion being continuous, while that portion engaged by the edges of the body is partially cut away, forming toothlike projections indicated at 4 which extend within the slot and

preferably the spaces intermediate of the teeth are substantially equal in size to same, this being to provide ample strength for the support of the blade and also to lessen its conductivity so that the portion adjacent the glass will heat more readily than if the blade were entire; the wires 5 and 6 being attached at the opposite extreme ends of the blade.

55 In Figure 3 I have shown the modified form of body portion supporting a pair of blades, 60 the latter being indicated at 7, which blades are similar in construction to the blades 3 heretofore described, and the body at 8. An insulating lining 9 is provided similar to the lining 2 in the device previously described. 65 Intermediate of the blades 7 is the arcuately shaped portion 10 of the body, the edges of which not only cooperate in the holding of the blades but act as positive spacing means for same. As is obvious the blades in this 70 modified form, or that shown in the other views of the drawings, may be secured within the clamping edges of the body portion by suitable through rivets within the spaces intermediate of the teeth 4 on the back of the 75 blade.

The portion 10 is provided with arcuate, staggered cut-out strips 11 which are bent downwardly for holding a sheet rubber wiper 12, which is preferably wrapped about a solid 80 or tubular metal core 13 for holding same firmly in position, the protruding edges lying flatly against each other and forming a wiper which engages the surface of the glass rearwardly of each member 7 as the 85 squeegee is operated from side to side. This rubber wiper is particularly for the purpose of removing only moisture from the glass as the scraper is supposed to be sufficiently adequate to remove all the harder material therefrom.

90 It will be noted that the wiping surface of the wiper 12 extends below the plane in which the edges of the scrapers 7 lie. As the squeegee moves back and forth over the pane 95 of glass the friction between the glass and wiper 12 will rock that scraper moving in front of the wiper into engagement with the glass. Therefore, if there is ice or snow on the glass one or the other of the scrapers 100

7 will be in contact with the ice or snow melting it and scraping it from the windshield and immediately thereafter the wiper 12 will wipe the moisture from the glass. As soon as the squeegee reaches the end of its travel in one direction and commences to travel in the opposite direction the squeegee will be rocked axially so as to bring the other scraper which will now be the forwardly moving 10 scraper into scraping contact with the glass and it will be followed by the wiper 12.

Having thus described my invention, what I claim and desire to secure by Letters Patent is

- 15 1. A squeegee comprising a tubular body portion having diverging marginal extremities, an arcuately shaped cooperative portion spaced from said marginal edges forming slots between the edges of the cooperative 20 portion and said margins, a heating blade within each slot thus formed engaged by both marginal edges of the body and said cooperative portion, and an electric connection for said blades.
- 25 2. A squeegee comprising a body portion adapted to rock having diverging marginal cleaning extremities, heating means associated with said extremities, a resilient cleaning member intermediate of the cleaning extremities and in constant engagement with the surface to be cleaned whereby when the squeegee is operated in either direction one or the other of the cleaning extremities will be caused to engage said surface.

30 3. In testimony whereof I affix my signature.
ARVID WICKSTROM.
